CONNECTING-CIRCUIT FOR TELEPHONE SYSTEMS.

1,303,960.

Specification of Letters Patent.

Patented May 20, 1919.

Application filed July 19, 1917. Serial No. 181,575.

To all whom it may concern:

Be it known that I, RALPH L. QUASS, a citizen of the United States, residing at Hawthorne, in the county of Passaic and 5 State of New Jersey, have invented certain new and useful Improvements in Connecting-Circuits for Telephone Systems, of which the following is a full, clear, concise, and exact description.

10 This invention relates to a connecting circuit for telephone systems, and more particularly to a circuit which may be used to supplement the connecting circuits of a call distributing system or may be used independently as an A operator's cord circuit.

In call distributing systems it is customary to provide apparatus which operates automatically to extend the circuit of a calling line to any one of a number of operators' positions that is at the time available, and to provide each operator with means for extending the connection of the calling line to a called line, as by inserting into a 20 spring-jack of the called line the plug of the connecting cord to which the calling line has been extended. In the operation of such systems, it sometimes happens that it is desirable for the operator to have means for establishing connection between the calling 25 and the called line independently of the call distributing connecting circuit over which the call has reached her; as, for instance, when the normally-established connection is accidentally interrupted, or when the normally-established connection is noisy and request is made for another connection, or 30 when the called line is busy or does not answer and the request is made that an attempt be made to establish the connection later, or 35 when other connections of an extraordinary nature are to be made. The particular object of this invention is to provide a connecting circuit having the special characteristics that will enable the operator to meet these 40 and other special service conditions, and which also will be adapted for use in answering calls and establishing connections in the ordinary way.

The preferred embodiment of the invention is shown in the accompanying drawing, in which Figure 1 illustrates diagrammatically two telephone lines with the associated apparatus at the subscribers' stations and the central office, and indicates circuits and

apparatus over which calls from these lines 55 normally reach an operator's position; and Fig. 2 illustrates the circuits and apparatus at an operator's position, including the call distributing connecting circuits for normally completing connection, and the special connecting circuit over which the operator is enabled to establish alternative connection with the calling and called subscribers' lines.

As indicated in the drawing, the organization over which the calling subscriber's line is normally extended to the operator's position may comprise a finder circuit F terminating at one end in the brushes of a switch LF through which the finder circuit 70 is brought into connection with the terminals of the calling line, and at the other end in the brushes of a switch CS by means of which the finder circuit may be brought into connection with the terminals of an available connecting circuit terminating in the plug 170 at the operator's position.

It will be sufficient merely to outline the manner in which a connection is established between a calling subscriber's line and a 80 called subscriber's line in the normal operation of the system, for the reason that the invention is particularly concerned with the special cord circuit, and the normal mode of establishing connection has only an incidental bearing thereon. If it be assumed that the subscriber at station A takes his telephone receiver from its hook, a circuit is completed for the energization of the associated line relay 12 by way of the resting 90 contacts of the corresponding cut-off relay 11. The line relay in operating may bring about the operation of the line finder switch LF, in a manner that need not here be described, to extend the circuit of the 95 calling line to the conductors of the finder circuit F, or to the conductors of a similar finder circuit the provision of which is indicated by the switch brushes LF' and CS'. The extension of the calling line to the 100 finder circuit F brings about the operation of the associated cord selector switch CS to further extend the circuit of the calling line to the cord circuit C. When this occurs the operator's telephone apparatus 147 may be 105 brought into connection with the cord circuit C by the operation of the switches 308, 309, 310 and 311 under the control of a

sequence switch motor magnet 300. The movement of these switches into their alternate position breaks the continuity of the cord circuit, and reestablishes the circuit by 5 way of that portion of the operator's telephone circuit which includes the ring-back key 160. The operation of the key 160, when occasion arises, interrupts the continuity of the cord circuit and applies ringing current from the ringing generator 63 to the part of the circuit which extends back to the calling subscriber's line.

When the operator's telephone set 147 is brought into connection with the calling 15 subscriber's line in the manner described, the operator is enabled to inquire and be informed of the number of the line with which connection is desired. When the operator has obtained this information, she 20 tests the called line by touching the tip of the plug 170 to the sleeve of the called line spring-jack, as 14', and, if the line is not in use, establishes connection by inserting the plug. When the plug is inserted, ringing 25 current is applied to the called line by moving the switches 518 and 519 to engage their alternate contacts. This applies ringing current from the generator 181 and rings the bell at the called subscriber's station. 30 The line relay of the called line has in the meantime been disconnected from the line by the operation of the associated cut-off relay 11', this relay being energized by the circuit established from battery through the 35 winding of the relay 175, sleeve of the calling plug 170 and corresponding contact of the called line spring-jack, and the winding of the cut-off relay 11' to ground. The energization of the relay 175 disconnects the 40 tip of the calling plug from the test conductor 133 and connects it with the tip strand of the connecting circuit. When the called subscriber responds, the talking circuit between the calling and called stations is completed through the repeating coil 139 45 imposed in the usual manner in the talking conductors of the cord circuit. The supervision of the connection may be controlled in the usual manner through the medium of 50 the answering supervisory relay 171 and the calling supervisory relay 187. While the connection is established the contacts of the switch 152 are closed. Upon the termination 55 of the conversation, the plug 170 is withdrawn and the contacts of the switch 152 are opened. When this occurs, the circuit is broken that had previously existed from battery by way of resistance 155, closed contacts of the switch 152, closed contacts of 60 the switch 217 of the finder circuit, the winding of the finder circuit relay 30, closed contacts 212, finder circuit conductor 50 and line conductor 53, and winding of the cut-off relay 11 to ground. The opening of this 65 circuit releases the cut-off relay 11 and the

finder circuit relay 30, and the release of the latter relay may effect the restoration of the line finder switch LF and the cord selector switch CS in a manner that need not here be described.

For a complete understanding of the circuit the operation of which has been described in outline in the foregoing, reference may be had to an application to S. B. Williams, Jr., (Serial No. 107,090 filed July 1, 1916).

The sequence switches that will be referred to in the description that follows may be of the type disclosed in Patent 1,127,808 issued February 9, 1915, to Reynolds and Baldwin. Each consists of an electromagnetically controlled motor or driving mechanism and a number of associated switch cams. The cams associated with the sequence switch 400 are designated 401 to 411 inclusive; those associated with the sequence switch 500 are designated 501 to 510 inclusive. To each of the contacts associated with the various sequence switch cams are applied certain numerals. These numerals in the case of the cams 401 and 501 indicate the only positions of the associated sequence switch in which these particular contacts are open; the numerals applied to all the other contacts of each sequence switch indicate the only positions of the particular associated switch in which the corresponding contacts are closed.

In order to convey an understanding of the organization and mode of operation of the special connecting cord circuit, one of the special conditions under which that cord circuit is used will now be assumed. The condition that will be assumed is that a call has reached the operator's position by way of the call distributing apparatus and the regular cord circuit C, and that when the operator attempts to take the order from the subscriber, she finds the connection noisy, presumably due to some trouble in the connecting circuit. In this case, the operator, instead of attempting to complete the establishment of the connection by inserting the calling plug 170 of the regular connecting circuit C in the spring-jack of the called subscriber's line, inquires the number of the calling subscriber and proceeds to establish the connection by means of a special connecting circuit S.

Having learned the number of the calling subscriber's line, the operator picks up the answering plug 31 of the special connecting circuit S, and inserts the plug in the multiple spring-jack 14 of that line, it being assumed that the calling line is the one represented as extending from station A. At the same time the switch 152 of the regular connecting circuit C is operated to open its contacts, as a result of which the finder circuit F is disconnected from the calling subscriber's

line and from the regular connecting circuit C and the circuits F and C are returned to normal.

- In inserting the answering plug 31 of the 5 special connecting circuit in the multiple spring-jack 14, the tip of the plug first touches the thimble or sleeve of the spring-jack. This completes a circuit that produces a click in the operator's telephone receiver which serves as a partial check upon 10 the correctness of the connection, as the line that is being connected with at the time has not yet become disconnected from the line finder switch LF over which the call was first transmitted to the operator, and therefore 15 has a potential on the conductor connected with the sleeve of the spring-jack 14. This potential causes a flow of current by way of the tip of the plug 31, left-hand armature and back contact of relay 41, and winding of relay 35 of the operator's telephone apparatus to ground. The relay 35 20 is energized and closes a circuit that extends from battery through the winding of the retardation coil 36, front contact and armature of relay 35, and test winding of the operator's induction coil 146 to ground, thus producing a click in the operator's telephone receiver.
- When the answering plug 31 is fully inserted in the spring-jack 14, a circuit is 30 closed that extends from battery through the winding of the relay 41, winding of relay 45, corresponding sleeve contacts of the answering plug 31 and spring-jack 14, and winding of the cut-off relay 11 of the calling subscriber's line to ground. The completion of this circuit continues the energization of the cut-off relay 11 to keep the line relay 40 35 disconnected from the calling subscriber's line, and also operates the relays 41 and 45 of the special connecting circuit. The relay 41 in operating disconnects the tip of the answering plug from the test conductor and 45 connects it through to the corresponding talking conductor of the connecting circuit. The relay 45 in operating closes a circuit that extends from battery, through the resistance 46, answering supervisory lamp 47 50 and left-hand front contact and armature of relay 45 to ground. But the answering supervisory lamp 47 remains dark, as the energization of the answering supervisory relay 51, when the answering plug 31 was inserted, has closed about it the shunt path 55 including the resistance 52. In operating, relay 45 also closes a circuit that extends from battery through the left-hand winding of the relay 42, right-hand back contact and armature of relay 40, and right-hand front contact and armature of relay 45 to ground. Relay 42 in operating closes a circuit that 60 extends from battery through the motor magnet and contact 402 (1) of listening sequence switch 400, inner front contact and 65

left-hand armature of relay 42, right-hand back contact and armature of relay 40, and right-hand front contact and armature of relay 45 to ground. The closure of this circuit moves the listening sequence switch 400 70 out of position 1, and the switch thereupon continues to move under the control of its cam 401 until it reaches position 7, where it comes to rest.

In passing through positions 2 to 6 sequence switch 400 closes a circuit by way of contact 415 (2 to 6), conductor 421, spring 320 (7) for the motor magnet of the sequence switch 300 of the connecting circuit C. Sequence switch 300 moves out of the 80 listening position in which it has been standing up to this time and in so doing opens the circuit of a relay 161 which in turn allows the switch contact 152 to open. This causes the restoration of switches LF and CS and 85 cord circuit C in the manner fully described in detail in the above mentioned application to Williams, Serial No. 107,090.

In moving to position 7, the listening-key sequence switch closes a circuit that extends 90 from battery, through resistance coil 54, calling signal lamp 55, ringing sequence switch contacts 504 (1 to 2), listening sequence switch contacts 405 (2 to 7), and calling signal interrupter 56 to ground. The result 95 of the closure of this circuit is to cause an intermittent display or flashing of the lamp 55 that continues while the sequence switch 400 is in its listening-in position and until the calling plug 32 is inserted. The movement of the listening key sequence switch 100 to position 7 also operates the listening key sequence switch cams 408, 409, 410 and 411 to interrupt, at contacts 408 (8 to 6) and 409 (8 to 6), the through circuit of the talking conductors of the connecting cord and to connect at the contacts (6 to 8) of the cams 408, 409, 410 and 411, a loop extending to the operator's telephone set and including the ring-back key 160. As a result of the 105 closure of this loop circuit, the operator's telephone set is connected with the special connecting circuit S by way of the resting contacts of the relay 57 and the cams 408, 409, 410 and 411 of the listening key sequence switch.

The operator is thus automatically brought 110 into communication with the calling subscriber by way of the answering cord of the special connecting circuit that has been substituted for the regular circuit C, and by speaking to the calling subscriber is able to verify the fact that he is the one whose call reached her a moment before by way of the regular connecting circuit C. Having ascertained this fact and being informed of the 120 number of the line to which the calling subscriber wishes to be connected, the operator tests the multiple spring-jack of that line, and, if the line is free, completes connection 125 130

with it by inserting the calling plug 32 of the special connecting circuit into the spring jack, which may be assumed to be the one associated with the line extending to station 5 B. The test circuit extends from the tip of the calling plug 32 by way of the left-hand armature and back contact of relay 33 and the winding of relay 35 of the operator's telephone apparatus to ground, and the energization of the relay 35, in case the called line is busy, causes a click in the operator's telephone receiver in the same manner as has already been described in connection with the test made by the answering plug 31. 10 15 When the calling plug 32 is fully inserted in the spring-jack 14', a circuit is completed that extends from battery, through the windings of the relays 37 and 33 in series, the coöperating sleeve contacts of the calling 20 plug 32 and the called line spring-jack 14', and the winding of the cut-off relay 11' of the called line to ground. The cut-off relay 11' acts to disconnect the associated line relay 12' in the usual way. The relay 33 in 25 operating disconnects the tip of the calling plug 32 from the test relay 35 and connects it instead with the tip strand of the connecting circuit. The relay 33 in operating also closes a circuit that extends from battery through the left-hand winding of the relay 42 and the right-hand front contact and armature of the relay 33 to ground. This circuit is a maintaining circuit for the relay 42, which relay, as has been described, 30 35 was operated when the answering plug 31 was inserted. The relay 42, therefore, after being energized by the insertion of the answering plug, is held energized as long as either the answering plug 31 or the calling 40 45 plug 32 is inserted in a spring-jack, and thus a path to ground is maintained by way of the contact 402 (1) of the listening sequence switch for preventing the listening key sequence switch from stopping in position 1 as long as either plug is inserted after the relay 42 has been initially energized.

When relay 37 operates, as a result of the insertion of the calling plug 32, it closes a circuit that extends from battery through 50 the motor magnet and contact 502 (1) of the ringing sequence switch 500, right-hand front contact and armature of relay 41 (which relay is operated as a result of the calling plug being inserted,) and the right-hand front contact and armature of relay 37 to ground. As a result of the closure of this circuit the sequence switch 500 moves out of position 1 and stops in position 2. This closes a circuit that extends from battery 55 through the winding of the motor magnet and contact 403 (7) of the listening sequence switch, right-hand back contact and armature of relay 43 and ringing sequence switch contacts 505 (2) to ground. When 60 65 this circuit is closed, the listening key se-

quence switch 400 moves out of position 7 and comes to rest in position 15, its listening-out position. When the listening sequence switch reaches position 8, it closes a circuit that extends from battery through 70 the motor magnet and contact 503 (2) of the ringing sequence switch, and contacts 406 (8 to 15) of the listening sequence switch to ground. The closure of this circuit moves the ringing sequence switch out of position 75 2, and it continues to move until it reaches position 13. The listening sequence switch in moving out of position 7 operates the cams 408, 409, 410 and 411 to disconnect the operator's telephone apparatus and complete the direct connection of the talking strands of the connecting circuit S. It also opens at contact 405 (2 to 7), the circuit from the lamp 55 to the calling signal interrupter 56; and the ringing sequence 80 switch, when it reaches position 3, completes the circuit of the lamp 55 directly to ground by way of contact 504 (3 to 16) of that sequence switch. Therefore, the flashing of the lamp 55 is changed to a steady glow. 85 The calling supervisory lamp 58 is displayed as soon as the calling plug 32 is inserted, the circuit that causes the illumination of the lamp extending from battery by way of resistance 59, lamp 58, ringing sequence switch 90 contact 506 (1 to 17) and left-hand armature and front contact of relay 37 to ground.

When the ringing sequence switch 500 reaches position 12, a circuit is closed that extends from battery, by way of the winding of relay 60, left-hand armature and back contact of relay 61, back contact and armature, of relay 62, ringing sequence switch contacts 507 (12 to 13), ringing sequence switch contact 508 (3 to 13), right-hand 100 front contact and armature of relay 41 and right-hand front contact and armature of relay 37 to ground. As long as the armatures of relay 60 are unattracted, a circuit exists by way of the right-hand back contact and armature of relay 60 and contact 503 (4 to 13) for continuing the movement of the ringing-key sequence switch. When, therefore, relay 60 is operated by the closure of its energizing circuit, as traced, upon the 105 ringing sequence switch reaching position 12, the energizing circuit of the ringing sequence switch motor magnet is opened at the right-hand back contact and armature of relay 60 and the sequence switch comes to 110 rest in position 13.

In position 13 of the ringing sequence switch a circuit is closed for applying ringing current to the called subscriber's line. This circuit extends from the ringing generator 63 by way of the commutator 73, which acts to connect the generator and battery alternately with the circuit, ringing sequence switch contact 509 (13), winding 115 of relay 62, left-hand armature and front 120 125 130

- contact of relay 60, ringing sequence switch contact 511 (13), ring contact of the calling plug 32 and corresponding switch spring of the spring-jack 14', and thence over the associated conductor of the called subscriber's line to and through the bell at substation B to ground. The other conductor of the subscriber's line at the same time is grounded by way of ringing sequence switch contact 510 (13), and the tip of the calling plug 32 and corresponding spring of the spring-jack 14'. The relay 62 is so constructed, as by providing its core with a copper sheath, that it is irresponsible to the normal ringing current flow. When, however, the called subscriber takes his telephone receiver from its hook in response to the ringing of the bell, the increased current flow in the circuit causes the operation of the relay 62.
- 10 The winding of the relay 61 is included in the previously-traced path including the relay 60, but is normally short-circuited by the branch of the circuit extending serially through the back contact of the relay 62 and the left-hand back contact of the relay 61. When the relay 62 is energized by the response of the called subscriber, this short circuit is broken and the relay 61 is energized. When the relay 61 operates, it breaks this short circuit at its own left-hand armature and back contact so as to keep the short circuit open independently of its control by the relay 62; and also, at its right-hand armature and front contact closes a path 30 from battery including the resistance 64 in shunt of the path that extends from battery by way of the winding of the relay 60. The resistance 64 is of relatively low value as compared with the resistance of the relay 60, so that when the relay 61 operates, the current flow through the winding of the relay 60 is reduced to a point where the relay 60 releases its armatures. In doing so, the relay 60 interrupts, at its left-hand armature and front contact, the path over which the ringing current is flowing to the connecting circuit and at its right-hand armature and back contact, and closes an energizing path for the motor magnet of the 40 ringing sequence switch 500 by way of the contact 503 (4 to 13) of that switch. The result, therefore, is that the ringing sequence switch moves out of position 13 and stops in position 16, its next resting position. In 50 moving out of position 13, the ringing sequence switch interrupts at contacts 507 (12 to 13) the energizing circuit for the relay 61. In position 16 of the ringing sequence switch, a circuit is closed that includes the 60 calling supervisory relay 65, with battery, in series with the circuit of the called line; and as the called subscriber has taken his telephone receiver from its hook, the relay 65 is energized. In operating, the relay 65 closes the energizing circuit of the motor magnet of ringing sequence switch 500 by way of the contact 502 (16) of that switch. This moves the ringing sequence switch from position 16 to 17. The calling supervisory relay 65 in operating also closes a shunt path 70 by way of the sequence switch contact 507 (1 to 17) about the calling supervisory lamp 58. This extinguishes the lamp and notifies the operator that the called subscriber has responded.
- 75 When the subscribers replace their telephone receivers at the end of their conversation, the deenergization of the answering supervisory relay 51 and calling supervisory relay 65 causes the associated supervisory lamps 47 and 58 to be illuminated, and the operator takes down the connection by removing the plugs 31 and 32 from the spring-jacks in which they are inserted. The removal of the answering plug 31 deenergizes 80 the associated relays 41 and 45, and the withdrawal of the calling plug 32 deenergizes the associated relays 33 and 37. In positions 2 to 17 of the ringing sequence switch, a path exists from battery through 90 the winding of relay 66, and by way of contacts 512 (2 to 17) of the ringing sequence switch to the right-hand back contact of the relay 33, and also to the left-hand back contact of the relay 45. Therefore, when 95 either of the plugs 31 and 32 is withdrawn from its spring-jack, a path to ground for the energization of the relay 66 is completed by way of the back contact and armature of the corresponding relay 45 or 33. In 100 operating, relay 66 closes a locking circuit for itself by way of ringing sequence switch contact 512 (2 to 17) and the right-hand front contact and armature of relay 66. Relay 66 in operating also closes a circuit that 105 extends from battery through the motor magnet and contact 502 (2 to 17) of the ringing sequence switch, and left-hand front contact and armature of relay 66 to ground. As a result of the closure of this circuit, the 110 ringing sequence switch 500 moves out of position 17 and comes to rest in its 1 or normal position.
- 115 It will be remembered that after the relay 42 became energized as a result of the insertion of the answering plug, its energization was maintained by two paths, one of which extended to ground from the left-hand winding of relay 42 by way of the right-hand back contact and armature of relay 40 and right-hand front contact and armature of relay 45, and the other of which extended to ground by way of right-hand front contact and armature of the relay 33. As both relays 45 and 33 are released by 120 the withdrawal of the answering plug and calling plug, respectively, both of these paths are broken and the relay 42 releases its armatures. In doing so a circuit is completed that extends from battery through 130

the motor magnet and contact 402 (7 to 15) of the listening-key sequence switch and to ground by way of the right-hand back contact and armature of relay 42. When this 5 happens, the listening-key sequence switch is moved from either of the positions 7 and 15 in which it may be standing, and is caused to return to its normal or 1 position. The withdrawal of both plugs, therefore, results in the restoration of the circuits of the 10 special connecting cords S to their normal condition.

In order to illustrate other operative capabilities of the organization disclosed herein, 15 it will now be assumed that the operator has attempted to establish a connection by means of the regular cord circuit C, has found that the called subscriber does not answer, and has been requested by the calling 20 subscriber to call him when she is able to get the line that is being called. In this case, the operator after an interval tests the multiple spring-jack of the called line with the tip of the calling plug 32 of the 25 special connecting circuit. If the line tests free, she inserts the plug 32 into the spring-jack. Under these circumstances, the insertion of the calling plug does not bring about the application of ringing current to 30 the called line, for the reason that the circuit for moving the ringing sequence switch out of position 1, although closed at sequence switch contact 502 (1) and right-hand front contact and armature of relay 37, is open at the right-hand front contact and armature of relay 41, the answering 35 plug not being inserted. The operation of the relay 37 resultant upon the insertion of the calling plug 32 closes a circuit that extends 40 from battery by way of the left-hand winding of the relay 40 and the winding of the relay 43 in parallel, the right-hand back contact and armature of relay 41, and the right-hand front contact and armature of 45 relay 37 to ground. Relay 40 in operating closes a locking circuit for maintaining its energization by way of its left-hand front contact and armature and the left-hand armature and front contact of relay 37 to 50 ground. It also closes another locking circuit for itself that extends from battery through the right-hand winding of relay 40, and thence to ground by way of the inner and outer right-hand front contacts of relay 55 40 (closed together by the attraction of the right-hand armature of that relay), and, the right-hand front contact and armature of relay 33 to ground. A branch path also extends from the right-hand armature of relay 40 to the right-hand front contact of the relay 45, and is completed to ground when the relay 45 is energized by the insertion of the answering plug 31. Thus, after the relay 40 is initially energized by 60 65 the insertion of the calling plug 32 at a time

when the answering plug 31 is not inserted, and the relay 40 is not operated, it is maintained energized as long as either the answering or the calling plug remains in its spring-jack.

The effect of the energization of the relay 40 is to interrupt the path by which the insertion of the answering plug 31 and the operation of the relay 45 normally effects the initial energization of the relay 42, the interruption being at the right-hand back contact and armature of the relay 40. Therefore, if the calling plug 32 is inserted before the answering plug 31 is inserted, the relay 42 is not energized by the insertion of 80 the answering plug, and the listening-key sequence switch is not automatically moved out of its normal position and into its listening-in position 7.

Having inserted the calling plug 32 into 85 the spring-jack of the line that did not answer when connection was attempted by way of the regular connecting circuit C, the operator then tests the multiple spring-jack of the calling line by touching it with the tip of 90 the answering plug 31. If she finds that the calling line is free, she inserts the answering plug 31 into the spring-jack. The resultant operation of the relay 45, as has just been pointed out, does not operate the 95 listening-key sequence switch to bring the operator's telephone set into connection with the circuit. Relay 41 in operating, however, completes at its right-hand front contact and armature the circuit for moving the ringing 100 sequence switch 500 out of position 1, this circuit being already closed at sequence switch contact 502 (1) and right-hand front contact of relay 37.

In the operation described in the preceding part of this specification, the movement of the ringing sequence switch into position 2 caused the listening sequence switch to move out of position 7, and the movement of the listening sequence switch out of position 110 7 caused the movement of the ringing sequence switch out of position 2, after which it moved to position 13 where ringing current was applied.

But in the case now under consideration, 115 the listening sequence switch remains in position 1, and therefore does not operate either to control the ringing sequence switch or to be controlled by it. This condition is provided for through the agency of the relay 120 43, which, it will be remembered, has its winding in parallel with the left-hand winding of the relay 40, and which therefore was energized when the calling plug was inserted, and remains energized over the locking 125 circuit by way of the left-hand front contact and armature of relay 40 as long as the calling plug 32 is in its spring jack. Relay 43 in operating opens at its right-hand back contact and armature the path over which 130

the listening sequence switch is normally moved out of position 7 when the ringing sequence switch 500 moves into position 2. It also closes at its left-hand front contact 5 and armature an energizing circuit for the motor magnet of ringing sequence switch 500 by way of contact 503 (2) of that sequence switch. Therefore, when the ringing sequence switch is moved to position 2 as 10 a result of the insertion of the answering plug, it is moved through that position and into its ringing position, although the listening sequence switch is not energized to move its cams. Thus the insertion of the 15 calling plug before the insertion of the answering plug causes the called subscriber's line to be rung without connecting the operator's telephone with the circuit, a result that is of advantage, inasmuch as the operator 20 is thus enabled to proceed with the establishment of this special connection without interfering with her regular work.

The calling subscriber is not rung until the called subscriber answers. The response 25 of the called subscriber is indicated by the extinguishing of the ringing lamp 55 and the calling supervisory lamp 58, both of which are lighted while the ringing sequence switch is in its ringing position. The operator 30 then brings her telephone into connection with the circuit by pressing the listening-in key 67. This closes a circuit that extends from battery through the right-hand winding of relay 42, listening sequence switch 35 contact 404 (1), and to ground by way of the contact and switch spring of the listening-in key. Relay 42 in operating closes a circuit that extends from battery through the motor magnet and contact 402 (1) of 40 the listening sequence switch, inner and outer left-hand front contacts of the relay 42 (closed together by the attraction of the left-hand armature of that relay), and thence to ground over two paths, one of 45 which extends by way of the inner front contact and right-hand armature of relay 40 and the right-hand front contact and armature of relay 45, and the other of which extends by way of right-hand front contact 50 and armature of relay 33. Relay 42 in operating also closes a locking circuit for itself by way of its left-hand winding and its left-hand armature and front contact and the two branch paths to ground just traced. 55 Therefore, after the relay 42 has once been operated by the pressing of the listening-in key 67, it remains operated as long as either plug is in its spring-jack, and prevents the listening sequence switch from stopping in 60 its normal or 1 position.

The movement of the listening sequence switch to position 7 in the manner just described, puts the operator into communication with the called subscriber; and she tells 65 him that he being called and asks him to

hold the line. She then presses the ring-back key 160 included in her telephone circuit loop. This applies ringing current to the calling subscriber's line and rings the bell at the calling station. At the same time, 70 the operator may operate the splitting key so as to spread the switch spring 69 and leave the switch springs 68 in their normal position. The result of this is to disconnect the talking strands of the calling cord from 75 the corresponding windings of the repeating coil 70 and connect them instead with the windings of the retardation coil 71. This destroys the inductive or talking connection between the calling half and the 80 answering half of the connecting circuit, and leaves the operator's telephone connected with the answering half, so that when the calling subscriber responds to the ringing of his bell, the operator may talk to him without the conversation being overheard by the called subscriber who is now waiting at his telephone. When the calling subscriber answers, the operator tells him that she has obtained the connection, and then puts the 85 two subscribers into communication by moving the splitting key to return the set of switch springs 69 to their normal position.

If before the operator puts the two subscribers into communication she wishes to 90 speak to the called subscriber without being overheard by the calling subscriber, she operates the splitting key so as to spread the switch springs of the set 68 without moving the switch springs of the set 69 from their 95 normal position. The result of this is to disconnect the talking strands of the answering cord from the corresponding windings of the repeating coil 70 and connect them instead with the windings of the retardation coil 71, thus destroying the talking connection between the two halves of the connecting circuit. At the same time, the spreading of the switch springs 68 closes a circuit that extends from battery through the winding of the relay 57, listening sequence switch contact 413 (5 to 7), and the lower contact and switch spring of the set 68 to ground. Relay 57 in operating disconnects the operator's telephone set from the loop 100 circuit controlled by the listening sequence switch cams 408, 409, 410 and 411, associated with the answering half of the cord circuit, and connects it instead, by way of the listening sequence switch cams 412 (7) and 414 105 (7), with the calling half of the connecting circuit. The operator's telephone set is thus disconnected from the answering cord and is connected with the calling cord of the 110 circuit.

After establishing the connection between the two subscribers, the operator disconnects her telephone set from the circuit by pressing the master listening-out key 72. This closes a circuit for the energization of 130

the motor magnet of the listening sequence switch by way of contact 403 (7) of that switch, and contacts of the listening-out key 72, and the listening switch thereupon moves 5 to position 15, the listening-out position. If the operator again should have occasion to connect her telephone set with the circuit, she may do this by pressing the listening-in key 67. This closes the energizing circuit of 10 the motor magnet by way of contact 404 (15) of the listening sequence switch and contacts of the listening-in key 67, and the listening switch thereupon moves to the listening-in position 7, passing through position 1 as a 15 result of the energizing circuit closed for its motor magnet in that position by way of sequence switch contact 402 (1), left-hand front contacts and armature of the relay 42, and the branch circuits to ground already 20 traced.

At the end of the conversation, the circuit is restored to its normal condition by the withdrawal of the answering plug and calling plug, the consequent deenergization of 25 relays 41 and 45 associated with the answering cord and relays 33 and 37 associated with the calling cord, opening the locking circuits of the relays 40, 42 and 43 and closing the circuits for the return of the listening sequence switch and the ringing sequence switch to normal, as already described.

There is a common connection from the contact 402 (7) of all of the listening sequence switches of the operator's position to 35 ground by way of common conductor 421 and the contacts 415 (2 to 6) of all of these listening sequence switches. The common conductor 421, as shown in Fig. 2, is also multipled to contacts of sequence switch springs 320 of 40 all the sequence switches 300 of the regular connecting cords C. As a result of this connection, any listening sequence switch in moving to its listening-in position 7, applies a ground for the energization of the motor 45 magnet of any other listening sequence switch that may be standing in position 7, so that the connection of the operator's telephone set with any of the circuits causes the automatic disconnection of the set from any 50 other circuit with which at the time it may be connected.

Another one of the special circumstances under which the operator may use the special connecting circuit S, is when she has 55 accidentally made connection with and signaled the wrong line on a call that has reached her over the regular connecting circuit C. In this case, upon discovering her mistake, she brings her telephone set into 60 connection with the connecting circuit C, withdraws the plug 170 from the spring-jack in which it was mistakenly inserted, and inserts the calling plug 32 of the special circuit S into the spring-jack from which 65 the plug 170 has been withdrawn. She then

proceeds to establish the proper connection by way of the regular connecting circuit C, the special connecting circuit remaining connected with the line that has been falsely signaled. When the erroneously called subscriber responds, the calling supervisory lamp 58 which was lighted when the plug 32 was inserted in the spring-jack, is extinguished; and the operator then depresses the listening-in key 67 associated with the 70 special circuit, thus operating the relay 42 and moving the listening sequence switch 400 into position 7 to bring her telephone set into connection with the connecting circuit S. As the answering plug 31 of the 80 special circuit is not inserted in a spring-jack, the energizing circuit for the motor magnet of the ringing sequence switch 500 by way of the cam 502 (1) is not completed, and the ringing sequence switch remains in 85 position 1. In position 1, the talking conductors of the connecting circuit are closed at contacts 510 (1) and 511 (1) of the ringing sequence switch, and the operator is therefore in telephonic communication with 90 the subscriber who has been falsely signaled, and may excuse the call. When the relay 42 was energized as the result of the depression of the listening-in key 67, it locked up by way of its left-hand winding, its left-hand armature and front contact, and the right-hand front contact and armature of relay 33 to ground. When the operator withdraws the calling plug 32 after excusing the false call, the relay 42 is deenergized, and 100 closes at its right-hand armature and back contact a circuit by way of listening sequence cam 402 (7 to 15), which disconnects the operator's telephone from the circuit and restores the listening sequence switch to position 1.

In addition to the foregoing and other special uses for which it is adapted, the special cord circuit is adapted to be used as an A-operator's cord circuit in answering calls 110 and directly establishing connections in the ordinary way. Such use may be illustrated by assuming that the line relays 12 and 12' of the two telephone line circuits shown act to cause the illumination of answering lamps 115 15 and 15' located in association, respectively with the spring-jacks 14² and 14³ of those lines, and shown connected with the front contacts of their respective relays by dotted line circuits. With the arrangement 120 assumed, when the telephone receiver is taken from its switchhook at either of the stations A and B, the corresponding line relay operates, and the associated line lamp lights. In response to the lighting of the 125 lamp, the operator inserts the answering plug 31 of the connecting circuit S into the associated spring-jack. The resultant energization of the relay 45 causes relay 42 to operate to move the listening sequence switch 130

400 into its listening-in position 7, thus automatically bringing the operator's telephone set into connection with the circuit. At the same time the lamp 55 is intermittently energized to give a flashing call signal, the answering supervisory lamp 47 remaining dark.

When the operator has learned the number of the line with which connection is desired, she inserts the calling plug 32 of the connecting circuit S into the spring-jack of that line, after testing the sleeve of the spring-jack with the tip of the plug 32 to ascertain whether or not the line is free for connection. The insertion of the calling plug 32 actuates the relay 37 to complete the closure of the circuit that energizes the motor magnet of the ringing sequence switch and moves it out of position 1. When it reaches position 2, the ringing sequence switch moves the listening sequence switch out of position 7 to disconnect the operator's telephone apparatus from the circuit; and in moving out of position 7, the listening sequence switch moves the ringing sequence switch out of position 2, from which position the ringing sequence switch then moves to position 13 and effects the application of ringing current to the called subscriber's line. When the called subscriber responds, the ringing sequence switch is moved to position 16, and then, through the actuation of the calling supervisory relay 65, is moved to the talking position 17, in which the conversational connection between the two subscribers is established. The lamp 55, which changed its flashing call signal to a steady illumination when the listening sequence switch moved out of position 7 and the ringing sequence switch moved into position 3, is extinguished when the called subscriber answers and the ringing sequence switch is moved out of position 16.

During the continuance of the connection, the operator may connect or disconnect her telephone apparatus with the connecting circuit by operating the listening-in key 67 or the listening-out key 72; or, if for any reason it becomes necessary, she may talk to either subscriber and exclude the other by operating one or the other of the set of switch springs 68 and 69 of the splitting key. When the subscribers hang up their telephone receivers at the end of the conversation, the supervisory lamps 47 and 58 are lighted, and the operator takes down the connection by withdrawing the plugs 31 and 32. The withdrawal of these plugs restores all the apparatus to its normal condition in a manner that has hereinbefore been described.

What is claimed is:

1. The combination with a connecting circuit having an answering plug and a calling plug, of operator's telephone apparatus,

an electromagnetic switch under the control of the answering plug for connecting said telephone apparatus with the cord circuit, and means under the joint control of the answering plug and the calling plug for rendering the answering plug inoperative to control said electromagnetic switch. 70

2. The combination with a plurality of telephone lines, of a connecting circuit provided with connecting switches for interconnecting said telephone lines, operator's telephone apparatus, an electromagnetic switch for connecting said telephone apparatus to the connecting circuit, and a relay under the joint control of said connecting switches 75 for rendering said electromagnetic switch either operative or inoperative dependent upon the sequence in which said connecting switches are closed.

3. The combination with a plurality of telephone lines, of a plug-terminated connecting circuit for interconnecting said lines, operator's telephone apparatus, an electromagnetic switch controlling the association of said telephone apparatus with said connecting circuit, said switch having a normal position, a listening-in position and a listening-out position, means actuated by the insertion of the answering plug for moving said switch out of its normal position and into 90 its listening-in position, means actuated by the insertion of the calling plug prior to the insertion of the answering plug for preventing such control of said switch by said answering plug, and means for preventing the 95 return of said electromagnetic switch to its normal position while either of said plugs is inserted. 100

4. The combination with a plurality of telephone lines, of a circuit for interconnecting the same, said circuit being provided with an answering connection switch and a calling connection switch, operator's telephone apparatus, a sequence switch for controlling the connection of said telephone 105 apparatus with said connecting circuit, said switch having a normal position, a listening-in position, and a listening-out position, a listening-in key, means actuated by the closure of said answering connection switch or 110 by the operation of said listening-in key for moving said sequence switch from its normal to its listening-in position, means for moving said sequence switch from its listening-in to its listening-out position, and 115 means actuated by the opening of both of said connection switches for returning said sequence switch to its normal position. 120

5. The combination with a plurality of telephone lines, of a plug-terminated circuit 125 for interconnecting the same, operator's telephone apparatus, an electromagnetic listening switch for controlling the connection of said telephone apparatus with said connecting circuit, means actuated by the insertion 130

of the answering plug of said pair before the calling plug is inserted for operating said switch to connect said telephone apparatus with the circuit, means controlled jointly by 5 both plugs actuated by the insertion of the calling plug before the insertion of the answering plug for preventing the insertion of the answering plug from actuating said switch to connect the telephone apparatus, 10 and manually operated switch mechanism operative when either plug is inserted for controlling the connecting and disconnecting operation of said listening switch.

6. The combination with a plurality of 15 telephone lines, of a circuit for interconnecting the same, said circuit being provided with an answering connection switch and a calling connection switch, operator's telephone apparatus, means actuated by the closure 20 of the answering connection switch for connecting said telephone apparatus with the connecting circuit, means actuated by the closure of the calling connection switch for disconnecting said telephone apparatus 25 from the circuit, independent means for controlling the connection of said telephone apparatus with and its disconnection from said connecting circuit, and means actuated by the closure of the calling connection switch 30 before the closure of the answering connection switch for making said independent means operative and preventing the closure of the answering connection switch from causing the connection of said telephone 35 apparatus with the circuit.

7. The combination with a plurality of telephone lines, of a circuit for interconnecting the same, said circuit being provided with an answering connection switch and 40 a calling connection switch, operator's telephone apparatus, means actuated by the closure of the answering connection switch for connecting said telephone apparatus with the connecting circuit, means actuated 45 by the closure of the calling connection switch for disconnecting said telephone apparatus from the circuit, independent means for controlling the connection of said telephone apparatus with and its disconnection 50 from said connecting circuit, and means made operative by the closure of the calling connection switch before the closure of the answering connection switch for preventing the closure of the calling connection switch 55 from causing the disconnection of said telephone apparatus from the circuit.

8. The combination with a plurality of telephone lines, of a circuit for interconnecting the same, said circuit being provided 60 with an answering connection switch and a calling connection switch, operator's telephone apparatus, an electromagnetic switch controlling the connection of said telephone apparatus with said circuit, a listening-in 65 key, means actuated by the closure of said

calling connection switch and the operation of said listening-in key for actuating said electromagnetic switch to connect the operator's telephone apparatus with the circuit, and means made operative by the opening of said calling connection switch for actuating said electromagnetic switch to disconnect the operator's telephone apparatus from the circuit. 70

9. The combination with a plurality of 75 telephone lines, of a circuit for interconnecting the same, said circuit being provided with an answering connection switch and a calling connection switch, operator's telephone apparatus, an electromagnetic switch 80 controlling the connection of said telephone apparatus with said circuit, a listening-in key, means actuated by the closure of said calling connection switch and the operation of said listening-in key for actuating said 85 electromagnetic switch to connect the operator's telephone apparatus with the circuit, a listening-out key, and means made operative either by the opening of said calling connection switch or by the operation of 90 said listening-out key for actuating said electromagnetic switch to disconnect the operator's telephone apparatus from the circuit.

10. The combination with a plurality of 95 lines, of a circuit for interconnecting the same, said circuit having an answering connection switch and a calling connection switch, operator's telephone apparatus, a sequence switch for connecting said telephone 100 apparatus with and disconnecting it from said connecting circuit, manually operated switching mechanism, and means made operative by the closure of either of said connection switches for placing said sequence 105 switch under the control of said manually operated switching mechanism.

11. The combination with a plurality of telephone lines, of a connecting circuit provided with an answering plug and a calling 110 plug, operator's telephone apparatus, an electromagnetic switch controlling the connection and disconnection of said telephone apparatus with said connecting circuit, manual switching mechanism for controlling 115 said electromagnetic switch when either plug is inserted, and a relay under the joint control of said answering plug and said calling plug for automatically controlling said electromagnetic switch when the answering plug is inserted before the calling plug. 120

12. The combination with a plurality of telephone lines, of a circuit for interconnecting the same, said circuit being provided with an answering connection and a calling connection switch, an electromagnetic listening switch, an electromagnetic ringing switch, means made operative when 125 the answering connection switch is closed 130

first for rendering the operation of said ringing switch subject to the movement of said listening switch, and means made operative when the calling connection switch 5 is closed first for rendering said ringing switch independent of control by said listening switch.

13. The combination with a plurality of telephone lines, of a circuit for interconnecting the same, said circuit being provided with an answering plug and a calling plug, operator's telephone apparatus and an electromagnetic listening switch for controlling the connection of the same with 10 said connecting circuit, a source of ringing current and an electromagnetic ringing switch for controlling the connection of the same with said connecting circuit, means made operative by the insertion of said answering plug first for operating said listening switch and rendering the movement of said ringing switch subject to the movement of said listening switch, and means rendered operative by the insertion 15 of said calling plug first for rendering the movement of said ringing switch independent of the movement of said listening switch.

14. The combination with a connecting circuit having an answering connection 30 switch and a calling connection switch, of operator's telephone apparatus and an electromagnetic listening switch for connecting the same with the circuit, a source of ringing current and an electromagnetic ringing 35 switch for connecting said source with the circuit, reciprocal controlling means between said listening switch and said ringing switch made operative by the closure of said answering connection switch first, and 40 means made operative by the closure of said calling connection switch first for making said reciprocal controlling means inoperative and rendering said ringing and listening switches operable independently of each 45 other.

15. The combination with a plurality of telephone lines, of a connecting circuit having an answering plug and a calling plug, operator's telephone apparatus, an 50 electromagnetic listening switch for controlling the connection and disconnection of said telephone apparatus with said connecting circuit, means under the joint control of said answering plug and said calling 55 plug, and operative only if the answering plug is inserted before the calling plug, for controlling the operation of said listening switch, a source of ringing current, a ringing switch for connecting the same with 60 said connecting circuit, means under the joint control of both of said plugs and said listening switch for actuating said ringing switch, and means made operative when said calling plug is inserted before said 65 answering plug for depriving said listen-

ing switch of control over said ringing switch.

16. The combination with a plurality of telephone lines, of a plug-terminated connecting circuit for interconnecting the same, operator's telephone apparatus and a listening sequence switch for controlling the connection of the same with said connecting circuit, a source of ringing current and a ringing sequence switch for controlling the application of ringing current from said source to said connecting circuit, said listening sequence switch having a normal position, a listening-in position and a listening-out position, and said ringing sequence switch having a normal position, a ringing position and a talking position, means actuated by the insertion of the answering plug for moving said listening sequence switch from its normal to its listening-in position, means actuated by the insertion of the calling plug for moving said listening sequence switch to its listening-out position, means actuated by said movement of the listening sequence switch for moving the ringing sequence switch to its ringing position, means actuated by the response of the called subscriber for moving the ringing sequence switch to its talking position, means actuated by the withdrawal of either of said plugs for moving said ringing sequence switch to its normal position, and means actuated by the withdrawal of both of said plugs for moving said listening sequence switch to its normal position. 100

17. The combination with a plurality of telephone lines, of a plug-terminated circuit for interconnecting the same, operator's telephone apparatus, a switch for controlling the connection of the same with said circuit, a source of ringing current, an electromagnetic switch for controlling the application of ringing current from said source to said connecting circuit, and means operated by the insertion of both plugs and the movement of said first mentioned switch for actuating said electromagnetic switch to apply ringing current. 105

18. The combination with a plurality of telephone lines, of a plug-terminated circuit for interconnecting the same, operator's telephone apparatus, a switch for controlling the connection of the same with said circuit, a source of ringing current, an electromagnetic switch for controlling the application of ringing current from said source to said connecting circuit, means operated by the insertion of both plugs and the movement of said first mentioned switch for actuating said electromagnetic switch 115 to apply ringing current, and means actuated by the withdrawal of either plug for actuating said switch to disconnect ringing current. 120

19. The combination with a plurality of 130

telephone lines, of a cord circuit for inter-connecting the same, said cord circuit having an answering plug and a calling plug, a source of ringing current, a sequence of 5 switch for controlling the application of ringing current from said source to said connecting circuit, means made operative by the insertion of both plugs for moving said sequence switch out of its normal position and into its ringing position where it 10 applies ringing current to the connecting

circuit to ring the called line, means made operative by the response of the called subscriber for moving said sequence switch to disconnect ringing current from the circuit 15 and establish the talking connection, and means actuated by the withdrawal of either plug for returning said sequence switch to normal.

In witness whereof, I hereunto subscribe 20 my name this 13th day of July A. D., 1917.

RALPH L. QUASS.
